Filed May 8, 1972, Ser. No. 251,601

Term of patent 14 years

Int. Cl. D23—04

U.S. Cl. D23—139

FIG. 1 is a front elevational view of the agribuilding cooling pad plenum showing my new design.

FIG. 2 is a perspective view thereof.

FIG. 3 is a fragmentary rear elevational view thereof.

FIG. 4 is an elevational view of the end opposite that shown in FIG. 2.

FIG. 5 is an enlarged cross-sectional view taken on line 5—5 in FIG. 1.

The plenum is broken away in FIGS. 1, 2, and 3 for purposes of disclosure, with omitted portions being bracketed to indicate indeterminate length. The interior structures shown in FIGS. 1, 2 and 3 are understood to continue the length of the plenum. FIG. 3 is fragmentarily shown for convenience of illustration. In FIG. 5 the broken line representation of structure is shown for illustrative purposes only.

I claim:

The ornamental design for an agribuilding cooling pad plenum, as shown and described.
